UNITED STATES PATENT OFFICE

JOHN P. NORTHEY AND RODNEY V. NORTHEY, OF TORONTO, ONTARIO, CANADA

RAIL CLIP

Application filed December 13, 1930. Serial No. 502,171.

This invention relates to devices for securing rails to the ties of a railway track including tie plates and means holding the rails in position on the tie plates, and our object 5 is to devise retaining means with which slotted key bolts may satisfactorily be used. We attain our object by means of constructions which may be briefly described as follows: A tie plate is formed with ribs between 10 which a rail base may be positioned. A clip is provided which is fitted against the upper surface of the tie plate and extends over the top of the rail base. This clip is held in place by means of a key bolt extending up 15 through the tie and tie plate and provided with a wedge key engaging the upper surface of the clip. Preferably the clip is formed with two key seats at different distances from its under surface and is slotted 20 so that it may be slid to bring either key seat in alignment with the key. Thus a greater or lesser take-up is provided for any given position of the key. Preferably in either 25 position of the clip shoulders on the clip and tie plate will be engaged to prevent swinging of the clip relative to the bolt.

The invention is hereinafter more specifically described and is illustrated in the accompanying drawing in which

30 Fig. 1 is a cross section of a rail, tie plate and clip;

Fig. 2 a plan view of a single clip and part of a tie plate and rail;

Fig. 3 a section on the line 3—3 in Fig. 2;

35 Fig. 4 a cross section of part of a rail, tie plate and a clip, showing a modification of the invention;

Fig. 5 a plan view of a modification of the clip;

40 Fig. 6 a plan view of another modification of the clip; and

Fig. 7 a plan view illustrating the mode of manufacture of the clip shown in Fig. 6.

Referring to the drawing, 1 represents a 45 tie and 2 a tie plate provided with ribs 3 forming a recess for the base 4 of a railway rail. 5 are clips, each having an end 6 adapted to extend over the rail base, as shown, but preferably out of contact therewith, so that the 50 rail may spring upwardly to a limited extent

without imposing a stress on the clip. Each clip engages a surface 7 of the tie plate on which it is adapted to slide to and from the rail. Shoulders 8 and 9 are adapted to interengage to limit this movement in either direction.

Each clip is formed with a slot 10. A key bolt 11 passes up from the tie, the tie plate, and the slot 10. Through the slot of the key bolt a wedge key 12 is adapted to be driven and to engage the back of the clip at different places according to the position of the clip relative to the rail. Preferably the back of the clip is formed with definite key seats 13 and 14 positioned at different distances from the under surface of the clip and preferably separated by a rib 15.

It is evident from this construction that, assuming the parts to be in the position shown in Fig. 1 and assuming that the wedge key has been driven as far as possible through the slot in the key bolt and there is still insufficient take up, the wedge key may be removed, the clip shifted outwardly to bring the seat 14 into alignment with the slot in the key bolt and the wedge key 12 again driven into place. More than two key seats may be provided if desired, but two will usually be found sufficient.

In Fig. 4 we see a slight modification, the 80 interengaging shoulders 8^a and 8^b being inclined while the clip itself is provided with a tail 16 engaging the rib 17 on the tie plate. The under surface of this tail is substantially parallel to the surface 7 on which the clip slides. This tail serves to cause a lifting stress applied at the end 6 of the clip to be transmitted to the bolt much more nearly in the line of its axis than is the case in the form of the clip shown in Fig. 1.

The form of clip shown in Figs. 1 and 2 is such that it is most readily made as a malleable casting.

In Fig. 5 we show a form of clip adapted to be made from a rectangular bar of metal 5^a. 95 In this form the slot 10^a is open ended, the end 6^a being formed by the double portion of the bar.

In Fig. 6 we show a form of clip stamped out by a die press. As shown in Fig. 7, such 100

a clip can be cut without waste from a flat strip of metal. In this form the part 5^b corresponds to the part 5 of Figs. 1 and 2 and the part 6^b to the part 6.

5. What we claim as our invention is:

1. The combination of a tie plate; a clip resting on the tie plate and having an end adapted to extend over the base of a rail resting on the tie plate; a slotted key bolt passing through the tie plate and clip from below; a wedge key adapted to be driven through the slot in the key bolt in engagement with the clip; and interengaging shoulders on the tie plate and clip to prevent the latter turning on the tie plate.

2. The combination of a tie plate; a clip resting on the tie plate and having an end adapted to extend over the base of a rail resting on the tie plate, the said clip being longitudinally slotted; a slotted key bolt passing through the tie plate and the slot in the clip from below; and a wedge key adapted to be driven through the slot in the key bolt, the clip having bearing surfaces for the key at different distances from its tie plate engaging surface and at different points in its length.

3. A construction according to claim 2 in which the tie plate and clip are provided with shoulders adapted to interengage to prevent turning of the clip on the bolt when the bolt is adjacent either end of the slot in the clip.

4. A construction according to claim 2 in which the tie plate and clip are provided with shoulders adapted to interengage to prevent turning of the clip on the bolt when the bolt is adjacent either end of the slot in the clip and in which the clip is provided with a tail piece extending over and in engagement with an outer part of the tie plate.

5. A construction according to claim 2 in which the clip is movable along a plane at right angles to the axis of the bolt and definite key seats are formed on the clip at different points in its length.

Signed at Toronto, Canada, this 5th day of December, 1930.

JOHN P. NORTHEY.
